VOLUME CONTROL AND NOISE SUPPRES-
SION SYSTEMLester T. Fowler, Oaklyn, N. J., assignor to Radio
Corporation of America, a corporation of Dela-
ware

Application April 30, 1935, Serial No. 19,036

10 Claims. (CL. 250—20)

The present invention relates to a radio receiving detector-amplifier system and more particularly to volume control and noise suppression circuits.

5 In radio receivers using a diode detector variably coupled to an audio amplifier, as by means of a volume control potentiometer resistor, and specifically in cases involving a combined thermionic diode-triode or pentode tube used as a second 10 detector-first audio amplifier in a superheterodyne, considerable trouble has been encountered because of overloading of the grid circuit of the audio amplifier when the volume control was advanced to maximum position. The grid of the 15 audio amplifier usually has been operated with a fixed bias obtained from the voltage drop in a self bias resistor in the cathode lead, the resistor being by-passed by a large value capacitor, usually a 10 mf. electrolytic type. The grid of the 20 amplifier has commonly been connected to the coupling potentiometer in the diode circuit through a stopping condenser to isolate direct current or rectified carrier so that only the audio frequency component of the detected signal is 25 impressed on the grid.

It has usually been desirable, from the standpoint of cost and size of apparatus, to arrange the tubes and design a circuit that will give satisfactory performance with the above mentioned 30 detector-amplifier tube feeding directly into the grid circuit of a power output tube. This has occasioned the use of a duplex diode high mu triode tube, such as an RCA-75, and which operates at a very low value of substantially fixed grid bias, 35 say negative 1½ volts. When a strong signal was tuned in on the receiver a d. c. (direct current) voltage component from the rectified signal of the order of 20 volts has ordinarily appeared in the detector circuit across the resistors in circuit 40 with the diode, available for automatic volume control of the tubes ahead. If this signal is modulated 50%, an audio signal voltage of the order of 10 volts a. c. (alternating current) is available in the diode circuit. Under these conditions, 45 when the audio volume control has been turned to maximum, all, or a substantial amount, of this audio voltage was applied to the grid of the high mu a. f. (audio frequency) tube, it is seen that very serious overloading and distortion has resulted because of the fact that the audio voltage applied to the grid was several times the fixed bias 50 from the usual self bias resistor. Not only distortion in the grid circuit of the tube has taken place but also distortion in the diode circuit has 55 occurred because of the grid drawing current

from the diode circuit on the positive half of each cycle of the signal.

It is well recognized that what is known as "delayed detection" gives a certain amount of suppression of background noise from various sources such as thermal agitation of electrons, antenna pickup, etc., that is, quiet tuning between stations. This delayed detection has ordinarily been obtained by connecting the diode circuit return so as to obtain a small threshold negative 10 bias on the diode plate from the drop across a self bias resistor in the cathode lead of an associated amplifier. Delayed detection gives some distortion on certain weak signals and will not detect still weaker signals, but it is widely used on 15 automobile radio receivers because of simplicity and low cost. By reason of the novel arrangement and connections in my improved circuit, to be hereinafter described, the effect of electron flow in a portion of my circuit is employed in producing noise suppression by setting up a threshold bias without the use of additional elements and cost of apparatus. In accordance with prior 20 practice, noise suppression has been obtained by means of a complicated network including a self 25 bias resistor.

An object of my invention is to provide a simplified and inexpensive volume control in a thermionic detector-amplifier circuit whereby distortion arising from the above mentioned causes is 30 eliminated without increasing materially the cost and complication of parts in the receiver.

A further object of my invention is to provide a volume control system for a high amplification type of thermionic device or tube in an audio 35 amplifier wherein grid bias may be varied throughout a wide working range to prevent overloading and without introducing distortion.

A still further object of my invention is to provide simplified automatic noise suppression circuit for giving silent tuning between stations.

The novel features which I consider characteristic of my invention are set forth with particularity in the appended claims. The invention itself, however, both as to its organization and its method of operation, together with additional objects and advantages thereof, will best be understood from the following description of a specific embodiment when read in connection with the accompanying drawing, like reference 45 characters referring to similar parts in the different figures, and in which:

Figure 1 is a schematic diagram of a portion of a superheterodyne receiving system embodying a preferred modification of my invention.

Fig. 2 is a circuit diagram of a circuit that I have been using in radio receivers.

Fig. 3 shows a characteristic curve of the improved circuit that will serve to illustrate my invention, and

Fig. 4 is a schematic diagram illustrating a laboratory circuit that was used in obtaining the characteristic curve of Fig. 3.

In accomplishing the first named object of my invention it is desirable that the gain of the amplifier section of the detector-amplifier or diode-triode tube not be reduced, otherwise this would necessitate increasing the cost and/or complication of the apparatus as by the addition of another tube and accompanying circuit elements. In receivers for motor driven vehicles it is desirable to have maximum amplification with a minimum number of tubes and accessories in order to reduce battery drain and for the sake of compactness, etc. While the practice has been to avoid variable bias when using a volume control with a high mu tube as an audio amplifier because of serious distortion, variable bias has been used with certain low mu tubes, e. g. the RCA-85 type, without substantial distortion, since it has the characteristic that a substantial bias increase does not cut off the plate current, in other words, it has a low rate of change of mutual conductance with grid bias change.

Referring to Fig. 2 of the drawing, I have illustrated a circuit that I have employed in radio circuits and which follows some of the teachings of K. A. Chittick, patent application Serial No. 678,153, filed June 29, 1933, now Patent No. 2,047,003, of same assignee. The control grid of a low mu tube 2 of the RCA-85 type is directly and variably connected to a potentiometer resistor 21 in circuit with the diodes 15 and 16. It will be seen that, by reason of the direct connection, as the contact on the potentiometer 21 is advanced toward the maximum position, not only the a. f. voltage but the d. c. or rectified carrier component are simultaneously increased on the grid. In order to limit the plate current for the condition where the grid has impressed on it insufficient negative diode bias, a coupling resistor 12 of around 25,000 ohms, a high value relative to the anode resistance, is used in the plate voltage supply to the anode. The plate 50 of the tube 2 is connected through a stopping condenser 9 to a high mu power output tube 10. While this circuit has performed in a satisfactory manner with manually variable bias, it was found necessary to use a fairly high step-up transformer, e. g. a ratio of 1:4 for practical purposes, in an attempt to make up for the low gain of the low mu type tube 2. From the standpoint of fidelity of reproduction, cost, reduction in size and simplification of apparatus, it would be preferable, however, to use straight resistance coupling between tube 2 and the output tube 10 but the sacrifice in gain, with a low mu tube 2 would be too great. To obtain comparable fidelity with transformer coupling as with resistance, it 65 would be necessary to have a high impedance primary, meaning a large number of turns, and several times as many secondary turns, a transformer of excessively large proportions. To obtain the same gain with a transformer coupled low mu tube as with resistance coupled high mu tube would require as high as 1:10 step-up ratio. Such a transformer would be impractical if designed to give satisfactory operation.

In accordance with my invention I have found that a high mu tube may be operated satisfac-

tory without appreciable distortion throughout a relatively wide range of bias potentials on the grid when certain connections to the screen grid, hereinafter described, are made in accordance with the teachings of A. H. Turner, as disclosed and claimed in application Serial No. 482,193, filed September 16, 1930, now Patent No. 2,063,143, of same assignee. Turner discloses that in controlling volume in a radio frequency amplifier the cut-off point of screen grid tubes may be extended very substantially as the negative bias on the control grids is increased if the positive potentials on the screen grids are simultaneously increased in a certain manner.

Referring to Fig. 1 of the drawing, I have illustrated a portion of the circuit of a super-heterodyne receiver wherein an intermediate frequency amplifier for modulated carrier currents, including a pentode tube 1 with a tuned i. f. (intermediate frequency) input transformer secondary 3 and step-down output i. f. transformer 4, feeds a detector diode 15 in a combined second detector and first a. f. amplifier tube 8. The detector and amplifier may be in separate tubes if desirable. The output electrode or anode 34 of the tube 8 is resistance coupled through resistor 5, stopping condenser 9 and leak resistor 7 to a high mu power output tube 10. A loud-speaker 11 is shown connected through a transformer 13 to the output of the power stage.

It is advantageous to connect the second diode plate 16 to ground instead of tying it to the other diode plate 15 in accordance with usual practice. The effect of this connection is to more completely shield the signal diode 15 from the control grid 27 and thereby make it possible to obtain a lower minimum volume. It has heretofore been found in high gain sets, and with strong impressed signals, that there is sufficient capacity coupling between the diode and control grid to pass sufficient signal voltage to prevent obtaining desired low volume with minimum setting of the volume control on the diode.

Referring more in detail to my improved circuit, signal voltage from the driving transformer 4 is impressed between the diode plate electrode 15 and the cathode or source of electrons 17 of the tube 8, and the resulting detected signal voltage appears across resistors 19 and 21. The entire drop in voltage of the d. c. or rectified carrier component of the detected signal is used for biasing the modulated carrier frequency amplifier tubes, not shown, preceding the i. f. tube 1 for automatic volume control purposes, as indicated by the arrow at AVC. A portion of the d. c. voltage drop is used for automatically controlling the bias on the grid of the i. f. amplifier 1, as indicated by the connection to point 23.

The control grid 27 of the diode-triode tube 8 is variably connected to resistor 21, used as a potentiometer for controlling the audio voltage and thereby the volume output from the receiver. As the slider on the potentiometer 21 is advanced the d. c. bias increases as a function of the increased a. f. For the maximum positions, as shown, the a. f. as well as the d. c. component is at the maximum desired. It will, therefore, be impossible to overload the grid, that is for the positive audio swings on the grid to exceed the negative d. c. bias and draw grid current. In one sense this is an improvement over Heising 1,687,245, broadly considered, who provided diodes for increasing the negative grid

potential of an amplifier when large amplitude waves are applied and vice versa.

The feature that makes it possible to use a high μ tube in this manner resides in the use of a resistor 29 of the order of one megohm in series in the d. c. supply circuit of a screen grid 31 which may also be considered a first anode or an output electrode. The screen grid is by-passed to ground through a condenser 33 of the order of one-tenth mfd. This resistor 29 is of much higher value than ordinarily used for filtering purposes, and, in accordance with the teachings of Turner, above referred to, the screen grid is effectively floating for d. c. potentials and assumes different values depending upon the d. c. bias on the control grid. As the control grid becomes more negative, thereby reducing the space current, less current flows in the screen grid circuit with the result that the screen grid potential becomes increasingly positive, approaching the anode potential, a differential effect with respect to the grid voltage variation.

A suppressor grid 32 makes the screen grid current a constant quantity for different tubes to impart a definite characteristic to screen grid tubes in production. Otherwise, secondary emission, an uncertain quantity, would upset conditions to such an extent as to make it difficult to use the above arrangement for production.

For best operation, the values of the anode resistors 5 and screen resistor 29 are important. In the first place the value of the plate resistance load determines the gain, around 150,000 ohms, by way of example, giving a desired high gain. In an actual receiver that I have built in accordance with my invention, the plate load resistance 5 has been divided into two series sections, 5a being around 56,000 ohms and 5b being of the order of 100,000 ohms. Section 5b is by-passed to ground with a .05 mf. condenser 30 whereby the combination of resistor 5b and condenser 30 functions to boost low a. f. frequencies as well as provide additional filtering. At low frequencies the condenser 30 offers substantial impedance, thereby raising the load impedance to more nearly match the plate impedance and give greater output at low frequencies. The opposite effect takes place in the case of high audio frequencies. By way of additional example stopping condenser 9 was around .01 mfd. and resistor 1 around 560,000 ohms. With the desired gain obtained, the value of the screen resistor 29 is adjusted to give minimum distortion. I have found a value of 1 megohm for resistor 29 to be satisfactory with a load of the above amount in the plate circuit. The above values are given merely by way of illustration and should not be construed as limiting my invention.

In Fig. 3 I have shown a static curve A and dynamic curves B of the characteristics of my circuit. In Fig. 4 I have illustrated the fundamental circuit used in the laboratory for deriving the above curves. In deriving curve A, the control grid was adjusted to known values of negative bias voltage on a C battery source, and plate current in milliamperes was read on a meter M in the plate circuit, the plate voltage from battery B being 250 volts. Resistors 5 and 29 were 150,000 ohms and 1,000,000 ohms, respectively. The tube employed was very high μ in characteristic, the amplification factor

being around 800 and the internal plate resistance about 800,000 ohms.

While curve A illustrates the static or d. c. relation between the grid bias and plate current curves B represent the dynamic or a. c. operation at two values of grid bias selected at random, namely, -5 and -15 volts, and on the basis of corresponding fixed screen potentials, which occur in practice by reason of the a. f. by-pass condenser 33 in Fig. 1. For deriving curves the bias of grid 27 was set at, say -5 volts; then the corresponding screen voltage was determined; next, since in actual a. f. operation the screen voltage remains constant for a given signal grid bias, for reasons just given, the screen 15 was directly connected to a point on the B battery of the same voltage as that determined; then the d. c. bias on the signal grid was varied to obtain corresponding values of plate current. The resulting dynamic curves B show that the 20 tube can be worked at the point of the characteristic curve giving small distortion and at the same time permit the grid bias to be varied over a much wider range than normal.

While in accordance with my invention it is 25 desirable to employ a pentode having a screen potential that varies by reason of poor regulation in the screen circuit, it would be possible to operate a high μ triode with variable control grid bias as an a. f. amplifier, provided the anode is 30 connected through resistance in the anode circuit that is several times as high as the internal plate resistance. A tube, for example, having the characteristics of an RCA-75 type tube can be connected through a million ohm resistor to a voltage 35 source of around 1000 volts, an excessively high and impractical value. It will be seen that, as the control grid negative bias is increased, the plate current decreases, with the result that the impressed plate voltage rises by reason of the decreased voltage drop through the high anode resistance, thereby substantially delaying the point of cut-off. While such a modification can be 40 used with a tube designed to withstand the abnormal voltages it will be quite obvious that my 45 preferred modification is free of the disadvantages inherent in the proposed use of the high μ triode.

Another important aspect of my novel detector-amplifier circuit is that a substantial amount of 50 automatic noise suppression occurs in the arrangement employed, by reason of a delay bias on the detector. This action is desirable from the standpoint of silent tuning between stations. Although noise suppression from "delayed detection" bias, of an amount employed in compromise with fidelity and sensitivity of detection, is insufficient to give complete silent tuning between stations, the amount generally employed, and as obtained with my system, is enough to materially 55 reduce the background noise when the set is tuned off a carrier wave. I attribute this action to the fact that the tube 8 employed by me has a fine mesh control grid closely spaced to the cathode, and consequently a substantial electron flow to 60 the grid takes place at no signal bias. I desire to designate this effect as residual grid current. Such grid current occurs by reason of the "Edison effect" or contact potential, initial electron velocity, etc.

The resultant residual current continues to flow 65 in the grid circuit when the grid has applied voltage values up to about 1 volt negative, depending upon the tube construction, the amount varying with different tubes tested. Of the tubes 70

I have used the average voltage involved was around $\frac{1}{10}$ ths of a volt. For some purposes it may be desirable to employ tubes so designed as to give much higher residual grid voltage. Heretofore tubes have not been designed with the intention of causing grid current and many have considered such current undesirable. With sufficient resistance in the grid circuit, the grid biases itself to negative $\frac{1}{10}$ ths of a volt, in the above example, due to its own grid current. Since the grid of the tube is connected directly to the diode circuit, the $\frac{1}{10}$ ths volt is developed across the diode resistance network when a substantial amount of resistance is included in circuit by the volume control, and is in such a direction as to impress the negative bias voltage on the detector diode. This produces a delay or threshold voltage on the diode, so that for impulses below the threshold value the detector does not function, thereby reducing noise output from the receiver. Of course when the volume control is set at or near minimum, as in the reception of strong signals, the necessary voltage from the grid current for cutting off the diode is not developed for noise suppression, but in this case the noise is low and unobjectionable. In some cases the grid may be connected to a fixed point on the diode resistor and not related to the volume control that may be used elsewhere in the circuit. Since the tubes controlled by automatic volume control are connected to the resistor in the diode circuit, the suppression voltage will increase the negative bias on the controlled tubes over what it would otherwise be when tuning between stations, or in other conditions of signal level below a certain low minimum value.

It will be understood that there occurs also a residual electron flow from cathode to diode plate of the detector under the condition of no impressed potentials up to a certain amount, because of the Edison effect. The diode in the average of the tubes tested by me biases itself to about $\frac{1}{10}$ ths volt negative on the plate by reason of the current flow through the resistance in the diode circuit. This bias action by the diode per se should not be confused with delayed detection. The application of negative potential to the diode, from an external source as from the grid as above described, greater than the diode voltage, cuts off electron flow to the diode plate so that detection does not occur until an impressed signal is of sufficient magnitude to overcome this delay or threshold value. From one point of view the diode is biased beyond cut-off by the grid current. In accordance with my invention the residual grid voltage exceeds the residual diode voltage by a safe margin. In working with detector diode bias on low mu a. f. amplifiers in high fidelity receivers, where delayed detection was considered undesirable, Mr. George L. Beers found that in same rare cases in production, grids of low mu tubes drew current at a higher negative voltage than did the diodes used. Accordingly he took steps to insure against imposing a delay bias on the diode in such cases by preventing grid current flow as by means of a negative C bias on the grid. However, I have found the grid current to be useful in setting up a threshold bias for noise suppression without the use of added apparatus, cost, and complications. While this residual grid current would tend to produce distortion if present at all times, it is noted that it disappears when a signal above a certain low amplitude is tuned in by reason of the increased bias from the diode circuit.

These two actions, the delayed operation produced on the detector diode, and the increased negative bias on the control tubes ahead of the detector, resulting from the small amount of inherent or residual grid current flow, very materially aid in noise suppression when the receiver is tuned off carrier, or when a carrier is below a certain low minimum level. Either of these two actions may be used singly. While I have shown the detector as biased through the diode resistor by the grid of a high mu amplifier for noise suppression it is possible that some electrode other than the control grid can be especially designed for use as a source of delay bias on the diode, in which case it would be unnecessary to use a high mu tube.

What I claim as my invention is:

1. In a radio receiving system a first thermionic amplifier, a detector, and second thermionic amplifier, means for impressing modulated carrier current amplified by said first amplifier on said detector, a resistance network in circuit with said detector for developing therein the modulation and rectified carrier components, a conductive connection from the grid of said second amplifier to a portion of said resistance network, said grid being characterized by the fact that a substantial amount of residual grid current flows with impressed potentials below a certain level, whereby, by reason of said conductive connection a potential bias is developed in said resistance network by said grid current, said bias rendering said detector inoperative for impressed signal or noise energy below a certain predetermined minimum level.

2. The system as set forth in the next preceding claim characterized in that connections are provided to said network to derive a potential for automatic volume control of said first amplifier, whereby said bias developed by said residual grid current causes a decrease in amplification of the amplifier controlled.

3. In a radio receiving system a first thermionic amplifier, a detector, and second thermionic amplifier, means for impressing modulated carrier current amplified by said first amplifier on said detector, a resistance network in circuit with said detector for developing therein the modulation and rectified carrier components, a conductive connection from the grid of said second amplifier to a portion of said resistance network, said grid being characterized by the fact that a substantial amount of residual grid current flows with impressed potentials below a certain level, connections from said first amplifier to said network to derive a potential for automatic volume control thereof, whereby voltage developed by said residual grid current in said network causes a decrease in amplification of said first amplifier for input energy below a predetermined minimum level.

4. In a radio receiving system, a thermionic tube including a detector electrode, an additional electrode in said tube, a source of electrons for each of said electrodes, a resistance network providing direct current coupling between said electrodes, said additional electrode being characterized by residual electron flow thereto in the absence of impressed potentials above a certain level, the additional electrode being so arranged as to set up in said resistor a negative bias for said detector electrode that exceeds the bias that would otherwise be caused in said resistance network by residual current flow to said detector electrode, thereby preventing electron flow to said detector electrode for im-

pressed potentials below the threshold value established by the residual current flow to said additional electrode.

5. The invention as set forth in the next preceding claim characterized in that said additional electrode is the grid of a high mu thermionic amplifier.

6. In a modulated carrier signal receiving system, a thermionic diode detector having a plate, 10 a thermionic amplifier having a grid, a variable resistance network common to said detector and amplifier and constituting a direct current connection between said plate and grid for impressing detected signal components on said grid to 15 adjustably change the grid bias as a function of the changed audio component, said grid being characterized by the flow of a residual electron current through said resistance network in the absence of signals above a minimum level, for 20 biasing off said detector.

7. In a receiving system, a diode having a plate, and a high mu amplifier having a grid, a resistance network providing a direct current connection between the plate and said grid, 25 means for variably impressing diode bias on said grid from said network, said grid being characterized by residual electron flow thereto and through said network in the absence of impressed potentials above a certain level, the residual 30 grid current being greater than the residual diode current, said grid being so connected to said network as to negatively bias off said diode in the absence of signals above a certain minimum level.

35 8. In a radio receiving system a diode detector and a thermionic amplifier, means for impress-

ing modulated carrier signals on said detector, a resistance potentiometer in circuit with said detector for developing demodulated signal energy components therein, a direct conductive connection between the grid of said amplifier and a variable tap on said potentiometer for adjustable diode biasing, said grid being characterized by a residual electron current flow at values of diode bias below a certain minimum level, said grid current exceeding the inherent residual flow 10 in said detector, said grid current flow causing a potential in said potentiometer for biasing off said detector for the prevention of residual electron flow in said detector.

9. In a radio receiving system, a detector, 15 means for producing noise suppression comprising a thermionic device for generating a voltage to bias said detector with a threshold value beyond cut-off for signals below a certain minimum voltage level, connections from said detector to 20 said device for rendering the latter ineffective to generate said bias when receiving signals substantially above said level.

10. In a radio receiving system, an amplifier, 25 a detector for signals from said amplifier, means for producing noise suppression comprising a thermionic device for generating a negative bias by the "Edison effect", connections from said device to said amplifier for impressing said negative bias on the latter in the absence of signal 30 energy above a certain minimum level, connections from said detector to said device for rendering the device ineffective for the production of said bias when receiving signals substantially 35 above said level.
